FUEL SUPPLY SYSTEM

William A. Ray, Glendale, Calif., assignor to
General Controls Co., a corporation

Application June 8, 1944, Serial No. 539,377

9 Claims. (Cl. 158—117.1)

1

This invention relates to a system for supplying fuel to a burner, and more particularly to a safety system ensuring against escape of unignited fuel.

This application is a continuation in part of my application filed on January 1, 1944, under Serial No. 516,733.

In that prior application, a fluid fuel control system is described that ensures automatic interruption in the supply of fuel in response to the occurrence of a condition that would render the system unsafe. The main elements of the system are either directly or indirectly energized by a commercial source of electrical energy. As an example, the system may be caused to respond to the extinguishment of a pilot flame, to de-energize an electromagnetically operated valve.

Although systems of this general character are now well-known, they suffer from the disadvantage that when there has been a power failure from the commercial source, the mere resumption of the supply of power is insufficient to place the system into operative condition. It is necessary in such systems, to reset a valve manually, and where the power failure extends over a considerable portion of a community, the process of resetting all of the valves involves a considerable expense and time. In said prior application, this difficulty is overcome, it being unnecessary to reset any of the valves, and the system immediately resumes operation upon re-establishment of the power.

It is one of the objects of this invention to improve the system described in said prior application.

In the system described in said prior application, the controlling valve requiring resetting, and operated electromagnetically, is maintained open even upon power failure, and yet is closed in response to an unsafe condition. This is accomplished first, by providing a direct current electromagnet that has sufficient remanence to keep its armature or core in attracted position even when de-energized; and, second, by utilizing the power to provide an alternating de-magnetizing flux for the electromagnet. Normally, therefore, the remanence is neutralized and the electromagnetically operated valve responds to any control condition requiring it to close. But on power failure, the de-magnetizing force is absent, and the remanence is then effective to keep the reset valve open. This open condition is not dangerous, since the power failure causes another electromagnetically operated valve to close, thus interrupting the flow of fuel.

2

This system requires a source of unidirectional current for the operation of the reset valve. Since almost all sources of commercial power are alternating current, a rectifier must be provided. In addition, a safety control device is provided to respond to an unsafe condition, such as an extinguished burner flame.

It is another object of this invention to combine the function of the rectifier and the safety control device; and more particularly by using an electronic emission device that responds to the existence of a pilot flame and that also acts as a rectifier for the supply of unidirectional current to the reset valve.

10 It is still another object of this invention to effect a further simplification by operation of the main valve by unidirectional current derived from the electronic emission device. This is rendered possible by the use of an electronic emission tube that can pass power sufficient to operate an appropriately designed electromagnetically operated valve.

15 For example, a type of tube that can be effectively used for this purpose is a multiplier phototube. This tube is arranged to be energized by a commercial source of alternating current, and the output of the tube is unidirectional. The current flow depends upon the intensity of illumination of the photosensitive cathode. This intensity in turn is dependent upon the illumination created by the pilot flame.

20 It is still another object of this invention effectively to utilize such a phototube, both as a control device and as a source of unidirectional current for supplying power to the system.

25 This invention possesses many other advantages, and has other objects which may be made more clearly apparent from a consideration of several embodiments of the invention. For this purpose there are shown a few forms in the drawings accompanying and forming part of the present specification. These forms will now be described in detail, illustrating the general principles of the invention; but it is to be understood 30 that this detailed description is not to be taken in a limiting sense, since the scope of the invention is best defined by the appended claims.

35 Referring to the drawings:

Figure 1 is a diagrammatic view of a system incorporating the invention;

Fig. 2 is a wiring diagram of the system; and

Fig. 3 is a wiring diagram of a slightly modified form of the system.

The system may be utilized for the control of 50 fuel generally, such as liquid or gaseous fuels.

In the present instance a main burner 1, adapted for gas fuel, is illustrated in Fig. 1. It is supplied from an appropriate source of fuel supply, as through the pipe 2. The flow of fuel to the burner is controlled by a main fuel valve 3, shown also in Figs. 2 and 3. A pilot burner 4 provides a flame 5 for igniting the burner 1 when valve 3 is opened. This pilot burner 4 is shown as supplied through conduit 6 leading to the pipe 2 and arranged back of the valve 3, so that closure of valve 3 will not serve to shut off the supply of fuel to the pilot burner 4. The conduit 6 is shown as including a pilot burner valve 7, shown also in Figs. 2 and 3.

Both of the valves 3 and 7 are shown as electrically operated. Furthermore, the control is such that, in the event of an unsafe condition, such as extinguishing of pilot flame 5, both valves are caused to close. After the pilot valve 7 is closed, the arrangement is such that it will not re-open by mere re-establishment of the safe condition, but must be held open until the burner 4 is lighted and the flame 5 is re-established.

The safety control circuit includes a light-sensitive device, such as a phototube 8, that responds to the light produced by the pilot flame 5, to the substantial exclusion of any other light source, as by the aid of appropriate shields. A focussing device 9 may be used to project the light from flame 5 onto the light-sensitive electrode of tube 8.

The main valve 3 is diagrammatically illustrated in section in Fig. 2. It is shown as including a stem 10 carrying a magnetic member or armature 11. An electromagnet structure 12 serves to exert a pull upwardly upon the armature 11 to open the valve 3 when the electromagnet 12 is sufficiently energized. Preferably this valve structure is such that a relatively small current of the order of one watt is sufficient to lift the armature 11 for opening the valve.

Substantially the same type of structure is utilized for the pilot burner valve 7. In this case the electromagnet associated with the valve includes a pair of coils 14 and 15 wound upon a magnetic core 16. The arrangement is such that, once the armature 13 is released from the core 16, re-energization of the electromagnet does not cause lifting of the armature 13; instead, it must be urged upwardly toward the poles of the core 16 by the manual reset button 17. Accordingly, once the flow of fuel to the pilot burner 4 is interrupted by valve 7, such flow cannot be re-established until the button 17 lifts the armature 13 into the operative influence of magnetic member 16. Then while the valve 7 is held open, the pilot burner 4 can be ignited to re-establish the flame 5; and this in turn, causes operative energization of coil 14.

So long as this flame 5 is in existence, the phototube 8 serves to control the circuits associated with the valves 3 and 7, so as to maintain them in operative condition. As soon as the flame 5 is extinguished the phototube becomes inactive and these valves are caused to close.

One type of control circuit for effecting this result is illustrated in Fig. 2. In this arrangement, the phototube 8 is utilized to serve also as an electronic emission rectifier for supplying unidirectional current to the electromagnet 12 and to the coil 14 of valve 7. Accordingly, the phototube 8 serves a plurality of functions: not only is it a control device, but it also serves to transmit rectified current to the system, capable of directly operating main valve 3.

In order that the phototube 8 transmit a sufficient current for the operation of valve 3, it is shown as of the multiplier type. One such tube is known as the 931-A. It includes a photo-sensitive cathode 18 which emits electrons when its active surface is illuminated, as by the flame 5. The anode 19 finally receives the electrons produced in the tube by successive action of the electrons upon a number of auxiliary electrodes or secondary emitters 20, 21, 22, 23, 24, 25, 26, 27, and 28. In the present instance, nine such auxiliary electrodes are shown. In order that these electrodes serve effectively to reinforce the original electronic stream emanating from the cathode 18 by secondary emission, they are shown as connected by taps to the high voltage secondary coil 29 of a step-up transformer 30. The primary coil 31 may be connected to a commercial source of alternating current.

The operation of such a multiplier tube is well known. A relatively weak stream of electrons is dislodged from the photo-sensitive surface of cathode 18. This stream is greatly reinforced by secondary emission successively from the auxiliary electrodes 20 to 28 inclusive the active surfaces of which are successively encountered by the electron stream. The output current between the anode 19 and cathode 18 is unidirectional.

Thus, for the operation of the electromagnet 12, the anode 19 is connected as by conductor 32 with the electromagnet 12. The other terminal of electromagnet 12 is shown as connected by connection 33 to an automatic switch 34 which may be a thermostat or other condition responsive device. Thence, the current flows through connection 35 to the upper terminal of secondary coil 29. From the lower terminal of secondary coil 29, connection 36 leads to the cathode 18. The alternating current electro-motive force across the terminals of secondary coil 29 is rectified through the unidirectional flow of electrons between the cathode 18 and the anode 19. The electromagnet 12 is connected to receive this rectified current, by the aid of the circuit just traced.

This circuit is de-energized as soon as cathode 18 ceases to be illuminated by the pilot flame 5, and then valve 3 closes. However, upon re-establishment of flame 5, the electronic emission current passing through tube 8 is sufficient to re-energize the electromagnet 12, provided the automatic switch device 34 is closed.

As heretofore stated, the pilot burner valve 7 is arranged to close when there is a failure of the flame 5. However, it is arranged to be left open if there is a total failure of the power supply. In order to effect this result, use is made of a supplemental coil 15 on core 16. Coil 14, normally energizing the electromagnet, is supplied with unidirectional current through the phototube 8. However, it is so connected that the current flow is considerably less than the current flow through the main valve electromagnet 12. For this purpose, the coil 14 is connected in the lead between any one of the auxiliary electrodes 20 to 28, and a tap on the secondary coil 29. In the present instance the coil 14 is interposed in the lead from auxiliary electrode 28 and its corresponding tap 37. By appropriate choice of the auxiliary electrode, the quantity of current flow in coil 14 can be that most suitable; and therefore the magnetomotive force produced by the coil 14 is sufficient to maintain the armature 13 in attracted position, but

not sufficient to attract the armature 13 from its valve closing position.

The coil 15 is shown as directly connected in series with the primary coil 31 of transformer 30. This coil 15 has a magnetomotive force just sufficient to neutralize the magnetic remanence of core 16 when the coil 14 is de-energized.

This remanence, by appropriate choice of material for core 16, is such that it would retain the armature 13 in attracted position even when coil 14 is de-energized. Accordingly, in order that the armature 13 be released, the coil 15 must be energized, for neutralizing the remanence.

In the event of power failure, the coil 15 is not energized and, therefore, the remanence of core 16 retains the armature 13 in attracted position, if the armature happens to be in that position. The necessity of resetting each and every one of the valves, such as 7, that are installed in a district where the power failure occurred is avoided. Nevertheless, it is ensured that valve 3 closes when the power goes off, for electromagnet 12 is then de-energized.

Normally, without any power failure, the pilot burner valve 7 is maintained open only while flame 5 is in existence. As soon as flame 5 is extinguished, the phototube 8 becomes inactive. The electromagnet 12 is also de-energized, ensuring closing of the valve 3; and, at the same time, core 16 releases armature 13, thereby causing the closing of valve 7. The coil 15 acts to neutralize the remanence of core 16, ensuring release of armature 13. The unsafe condition created by the extinguishing of flame 5 thus sets into operation the safeguards that ensure against any flow of unignited fuel.

Valve 3 is independently controllable by the automatic switch or thermostat 34, which may respond to the temperature of the space to be heated. The valve 3 may be operated thereby to open and close, as required by temperature conditions.

In the form illustrated in Fig. 2, the coil 14 is provided with unidirectional current of appropriate potential difference below the potential difference applied to the electromagnet 12. This is accomplished, as heretofore stated, by interposing the coil 14 in the lead between one of the auxiliary electrodes and the secondary coil 29.

In the form illustrated in Fig. 3, the system operates substantially identically with that illustrated in Fig. 2, except that the reduced potential difference of coil 14 is obtained in a slightly different way. In this form of the invention the electromagnet 12 is supplied, as before, with unidirectional current as by appropriate connections 32, 33 and 35, as in the form illustrated in Fig. 2. The coil 14 is placed in parallel with the electromagnet 12; and a resistance 38 included in the circuit of coil 14 to reduce the potential difference across the coil.

The inventor claims:

1. In a system of the character described, a burner, an electrically operated valve for controlling the flow of fuel to the burner, a photo-electric tube having a photosensitive cathode and adapted to be energized from a source of alternating current, said device serving to rectify the alternating current, and supplying the resultant unidirectional current to operate said valve, and a light source affecting the cathode for controlling the flow of said unidirectional current.

2. In a system of the character described, a

burner, an electrically operated valve for controlling the flow of fuel to the burner, a photo-electric tube having a photosensitive cathode and adapted to be energized from a source of alternating current, said device serving to rectify the alternating current, and supplying the resultant unidirectional current to operate said valve, and a light source affecting the cathode for controlling the flow of said unidirectional current, said light source being active in response to a condition of operation of said system.

3. In a system of the character described, a main burner, a pilot burner for providing a pilot flame, an electrically operated valve for controlling the flow of fuel to the main burner, and a photo-electric tube having a photosensitive cathode and adapted to be energized by a source of alternating current, said device serving to rectify the alternating current, and supplying the resultant unidirectional current to operate said valve, the flame of the pilot burner supplying illumination for the cathode, to cause an operating unidirectional current to flow for electrically operating the valve.

4. In a system of the character described, a main burner, a pilot burner for producing a pilot flame, an electrically operated valve for controlling the flow of fuel to the main burner, an electrically operated valve for the pilot burner, having a magnetic member and a coil for magnetizing said member, an electronic emission device, adapted to be energized from a source of alternating current, said device serving to rectify the alternating current, and supplying the resultant unidirectional current to operate both of said valves, said electronic emission device including means causing flow of said unidirectional current of sufficient quantity to operate said main valve, only while the pilot flame is in existence, said device also supplying unidirectional current to the pilot burner valve coil for holding the pilot burner valve open, the remanence of the magnetic member being sufficient to retain the pilot burner valve open after the coil is de-energized, and a demagnetizing coil for the magnetic member and supplied from the source of alternating current, said demagnetizing coil operating to render said remanence ineffective while the source of alternating current is active.

5. In a system of the character described, a main burner, a pilot burner for producing a pilot flame, an electrically operated valve for controlling the flow of fuel to the main burner, an electrically operated valve for the pilot burner, having a magnetic member and a coil for magnetizing said member, a photo-electric tube having a photosensitive cathode and affected by the pilot flame, said tube being adapted to be energized from a source of alternating current, for supplying unidirectional current to operate the main valve only while the pilot flame is in existence, said device also supplying unidirectional current to the pilot burner valve coil for holding the pilot burner valve open, the remanence of the magnetic member being sufficient to retain the pilot burner valve open after the coil is de-energized, and a demagnetizing coil for the magnetic member and supplied from the source of alternating current, said demagnetizing coil operating to render said remanence ineffective while the source of alternating current is active.

6. In a system of the character described, a main burner, a pilot burner for producing a pilot flame, an electrically operated valve for controlling the flow of fuel to the main burner, an elec-

trically operated valve for the pilot burner, having a magnetic member and a coil for magnetizing said member, a multiplier photo-electric tube having a photosensitive cathode, an anode and intermediate electrodes, said cathode being affected by the pilot flame, said tube being adapted to be energized from a source of alternating current, the intermediate electrodes being connected to the source and having progressively higher electromotive forces, said tube supplying unidirectional current to operate the main valve only while the pilot flame is in existence, the coil for the pilot burner valve being supplied with unidirectional current derived from one of said intermediate electrodes, to hold the pilot burner valve open, the remanence of the magnetic member being sufficient to retain the pilot burner valve open after the coil is de-energized, and a demagnetizing coil for the magnetic member supplied from the source of alternating current, said demagnetizing coil operating to render said remanence ineffective while the source of alternating current is active.

7. In a system of the character described, a burner, a valve for controlling the flow of fuel to the burner, an electric circuit controlling the operation of the valve, a photo-electric tube having a photosensitive cathode and adapted to be energized from a source of alternating current, said device serving to rectify the alternating current, and supplying the resultant unidirectional current to operate said valve, a light source affecting the cathode for controlling the flow of said unidirectional current, and condition responsive means for independently controlling said circuit.

8. In a system of the character described, a main burner, a pilot burner for producing a pilot flame, a main valve for controlling the flow of fuel to the main burner, a circuit for operating the main valve, a valve for the pilot burner, a circuit for operating the pilot burner valve, said pilot burner having a magnetic member, said pilot burner valve circuit including a coil for

5 magnetizing said member; an electronic emission device, adapted to be energized from a source of alternating current, for supplying unidirectional current to both of said circuits, said device including means causing flow of said unidirectional current of sufficient quantity to operate said main valve only while the pilot flame is in existence, the remanence of the magnetic member being sufficient to retain the pilot burner valve open after the coil is de-energized, a demagnetizing coil for the magnetic member and supplied from the source of alternating current, said demagnetizing coil operating to render said remanence ineffective while the source of alternating current is active, and condition responsive means for independently controlling the circuit for the main valve.

9. In a system of the character described, a main burner, a pilot burner for producing a pilot flame, a main valve for controlling the flow of fuel to the main burner, a circuit for operating the main valve, a valve for the pilot burner, a circuit for operating the pilot burner valve, said pilot burner having a magnetic member, said pilot burner valve including a coil for magnetizing said member, a photo-electric tube having a photosensitive cathode and affected by the pilot flame, said tube being adapted to be energized from a source of alternating current, for supplying unidirectional current to operate the main valve only while the pilot flame is in existence, said device also supplying unidirectional current to the pilot burner valve coil for holding the pilot burner valve open, the remanence of the magnetic member being sufficient to retain the pilot burner valve open after the coil is de-energized, a demagnetizing coil for the magnetic member and supplied from the source of alternating current, said demagnetizing coil operating to render said remanence ineffective while the source of alternating current is active, and condition responsive means for independently controlling the circuit for the main valve.

WILLIAM A. RAY.
